UNITED STATES PATENT OFFICE

1,935,033

FABRIC EXPANDER

John LaTerra, Paterson, N. J.

Application September 28, 1931
Serial No. 565,598

3 Claims. (Cl. 26—57)

This invention relates to a device for expanding or stretching fabric, the general object of the invention being to provide a pair of endless members provided with cloth or fabric engaging clips for engaging the edges of the fabric with the parts so arranged that as the endless members travel along, the fabric is stretched in an easy manner to remove wrinkles and to stretch the fabric to the proper width, and continually dispose the fabric in the same place at the outlet end of the apparatus so that the fabric may be printed or wound in a perfect and straight line and perfectly aligned.

Another object of the invention is to provide adjusting means for properly spacing the endless members apart and to provide means whereby the clips engage the edges of the fabric at the inlet end of the apparatus and release the fabric at the outlet end thereof.

20. A further object of the invention is to provide means for tensioning the fabric before entering the apparatus, such means being especially designed for tensioning the fabric as the fabric is about to run off the roller upon which it has been wound.

Another object of the invention is to so form the device that it can be used in connection with a printing machine, a washing machine, a doubling machine, etc.

30. This invention also consists in certain other features of construction and in the combination and arrangement of the several parts to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:

40. Figure 1 is an elevation showing the invention used with a printing machine, the view being largely diagrammatic.

Fig. 2 is a top plan view of the invention.

Fig. 3a is a view partly in section of one end thereof, and showing the parts in elevation, with a projection for opening the clamps.

Fig. 3b is a similar view of the other end of the device, but showing a wheel for opening the clamp.

50. Fig. 4 is a cross sectional view of one of the supporting members.

Fig. 5 is a detail top plan view of one of the clips.

Fig. 6 is an elevation showing the invention used with a washing machine.

Fig. 7 is an elevation showing the invention used with a doubling machine.

Fig. 8 is a view partly in section showing mechanical means of speed control.

Fig. 9 is a top plan view of a doubling machine 60 with which the invention is used.

As shown in Fig. 2, the device comprises a pair of elongated frames A and B, each of which is of substantially inverted T-shape as shown at 1 in Fig. 4. The lower part of each member 1 is extended at each end as shown at 2 to form a seat for a sprocket 3. The shafts for the sprockets are shown at 4, and the upper end of each rear sprocket is covered by a member 5, suitably attached to the frame member and containing the anti-friction bearings 6 for the upper end of the shaft. Each extension 2 contains the anti-friction means 7 for the lower end of the shaft. Each of the rear sprockets has a worm gear 8 attached to its upper end which meshes with a worm 9 carried by a shaft 10 which extends across the two frames A and B as shown in Fig. 2. Thus by rotating this shaft, the drive sprockets of the two frames are rotated. The sprockets at the opposite ends of the frames are idle ones.

Each endless member is composed of a plurality of U-shaped clips 11 with their lower parts pivotally connected together as shown at 12, the clips being so formed that they can pass around the sprockets at the ends of the frames, and are guided by portions of the intermediate portions of the frames 1. The clips are provided with the depending projections 13 for engaging the teeth of the sprockets, so that the drive sprockets will impart movement to the endless members composed of the clips.

The upper part of each clip is of V-shape as shown at 12' in Fig. 5 and a shaft 14 in the ends of the limbs of each V-shaped part supports the 95 fabric engaging finger 15.

A curved member 16 is supported from the part 5 as shown in Fig. 3a to move the gripping fingers to open position through a wheel, such as shown at 16' in Fig. 3b, may be used to move the fingers 100 to open position at the ends of each frame.

Either the members 16 or the wheels 16' are engaged by the fingers as the clips pass around the sprockets, so as to move the fingers to releasing position. A lower L-shaped finger 30 105 is pivoted to each clip 11 as shown at 31 in Fig. 3a and an upper finger 32 is pivoted to the upper end of the short arm of the lower finger as shown at 33. The outer end of each finger 32 is pivoted to the lower end of the finger 15, as shown at 34. 110

The outer end of each finger 30 is adapted to engage in a recess 35 formed in the upper face of the lower part of each clip 11.

From the foregoing it will be seen that the 5 cloth gripping fingers 15 are in releasing position at the ends of the device, and as the cloth passes into the inlet end of the device, the edges will pass upon the upper surfaces of the lower parts of the clips 11 at the inlet end of the 10 device, and as the fingers 15 pass from the releasing means, either 16 or 16', their lower ends will engage the edges of the cloth, with the lower end of the lower fingers 30 also engaging the cloth.

15 As the cloth is stretched by the diverging devices, the edges will be pulled from under the lower fingers 30 so that the outer ends of these fingers will drop into the recesses 35, thus causing the lower ends of the fingers 15 to more firmly 20 clamp the cloth between themselves and the lower parts of the clips 11 so as to prevent further sliding movement of the edges of the cloth on the clips, and thus as the cloth passes through the machine, it will be stretched owing to the two 25 sets of holding devices moving away from each other as the endless members move towards the outlet end of the device. This stretching action will continue until the fingers 15 strike the releasing means 16 or 16' at the outlet end of the 30 device, when the fingers 15 will be moved to releasing position, and thus the cloth will be released at the outlet end of the device.

The upper edges of the members 1 have brackets 17 thereon, the dove-tailed grooves of which 35 receive the dove-tailed guides 18 supported on the beams 19 and shafts 20, which are supported for rotary movement by the beams 19, have threaded portions engaging threaded holes 21 in 40 parts of the brackets 17 so that by turning the shafts 20, the members A and B will be moved toward each other or away from each other, to increase or decrease the space between the two 45 devices A and B.

As shown in Fig. 2, the frames A and B are 50 slightly curved from one end to the other, so that the fabric is stretched as it is drawn between the members by the clips, and by turning the shafts 20, the space between the two members 55 can be adjusted to stretch the fabric to the desired extent.

50 Stationary rollers 22 support the cloth or fabric where it enters the stretching device and a number of rollers 23 are supported above the rollers 22. These rollers 23 are supported by a member 24 which may be actuated from a lever 25 through means of the linkage 26 so that by depressing the lever 25, the rollers 23 will be moved downwardly, so as to apply tension to the fabric at 27. Of course, this tensioning means can be 60 thrown into operation whenever desired, but it is mainly designed for use when the fabric is about to run off the supporting roller 28 shown in Fig. 1, for at this time the fabric will become loose and would be liable to wrinkle and it would be 65 a difficult matter for the clips to properly engage the fabric as it passes through the device.

However, by applying tension to the fabric at this time, by lowering the rollers 23, the clips will properly engage the fabric as it enters the device.

70 As before stated, this device can be used with a printing machine as shown in Fig. 1, as it will properly stretch and expand the fabric before it enters the printing device, so that the fabric will be properly printed as it passes through the 75 printing device.

Of course, the worms 9 are slidably attached to the shafts 10 so that these worms will be moved when the devices A and B are moved toward or away from each other by the rotation of the shafts 20.

80 The sprockets 3 at the inlet end of the device are adjustable so as to keep the endless members properly tensioned, the adjusting means being shown generally at 36, and consists of sliding blocks for the shafts of the sprockets arranged in slots in the supporting members, and screw shafts connecting with the blocks and passing through threaded holes in the supporting members as shown in said Fig. 2.

85 Fig. 6 showing the invention used with a washing machine, the tanks of which are shown at 37 and the rolls for guiding the cloth through the tanks are shown at 38. The wringing rolls are shown at 39 and after passing through these tanks, the cloth passes through the expanding device shown in this Figure 6 at C. After passing through the expander, the cloth passes over the expanding rolls 40 and then over the drying cans 41, and from these cans the cloth passes onto the take-up roll 42.

90 Figs. 7, 8 and 9 show the expander used with a cloth assembling machine. As shown in Figs. 7, 8 and 9, the expanding device, shown at D, is applied to a doubling machine. The shaft 10 of the expander device is driven from a motor M 105 and in Fig. 8 the transmission of the motion of the motor to the belt or chain 43 is controlled by a mechanical speed controlling means shown generally at 44 and which is of any well known construction and includes the reeves 45 and 46 and 110 the endless members or belt 47 with the screw shaft 48 for controlling the position of the belt on the reeves. This screw shaft is operated by a gear 49 with which meshes a gear 50 having a sprocket connected therewith over which an 115 endless chain 51 passes, and this chain also passing over an upper sprocket 52. A floating roller 53 is attached to the chain 51, and the cloth 54 on its way to the doubling machine, passes around this floating roller.

120 Thus as the floating roller is moved by the cloth, the chain 51 is moved and the gears 50 and 49 regulate the speed control means 44 through means of the screw shaft 48. Thus the operation of the expanding device B is controlled 125 by the movement of the cloth to the doubling machine, and this arrangement shown in Fig. 8 is designed for use when the motor is an A. C. one.

130 Fig. 7 shows a speed controlled arrangement for controlling the speed of the motor when the same is a D. C. one and as shown in this Fig. 7, the cloth 54' passes over the floating roller 53' which is carried by the links 55, and is guided by the guides 56. The links are connected to 135 the arms 57 of the rheostat 58 which controls the circuit of the motor M'. The cloth after passing around the floating roller 53' passes over the upper roll 59 and then over the doubling means 60 to the guiding roll 63 from which it 140 passes to the roll 64 to the take-up roll 65 or a reel. When the reel is used, one of the guide rolls 64 can be yieldingly supported, so as to deliver the fabric to the reel in a smooth and easy manner.

145 Thus the movement of the cloth through the doubling machine automatically controls the circuit to the motor M' which drives the expander D so that the cloth is perfectly aligned before entering the doubling machine.

As the printing machine, the washing machine, and the doubling machine may be of any well known or desired construction, it is not thought necessary to show and describe these in detail, but the drawings show how the expander can be used with such machines.

It is thought from the foregoing description that the advantages and novel features of the invention will be readily apparent.

10 It is to be understood that changes may be made in the construction and in the combination and in the combination and arrangement of the several parts, provided that such changes fall within the scope of the appended claims.

15 Having thus described my invention, what I claim as new is:—

1. A cloth stretching device comprising a pair of diverging supporting frames, endless members carried by said supporting frames, means for automatically attaching the edges of the cloth to the endless members as the cloth enters the machine, means for automatically detaching the cloth from the endless members as the cloth leaves the machine, means for actuating the endless members, spaced rollers at the front end of the frames over which the cloth passes before passing between the frames, a vertically movable member located above the rollers, spaced rollers carried by said member for pressing portions of the cloth between the first-mentioned rollers when said member is lowered and means for raising and lowering said member.

2. A cloth stretching device comprising a pair of diverging supporting frames, endless members carried by said supporting frame, means for automatically attaching the edges of the cloth to the endless members as the cloth enters the machine, means for automatically detaching the cloth from the endless members as the cloth leaves the machine, means for actuating the end-

less members, and front and rear transversely arranged members attached to each frame and each having a dove-tail groove therein, cross beams, dove-tailed members carried by said beams fitting in the grooves of the transverse members, a screw shaft supported by each beam and having right and left threaded portions, and ears on the transverse members having threaded openings therein through which the threaded portions of the shafts pass.

3. A cloth stretching device comprising a pair of diverging supporting frames, endless members carried by said supporting frames, means for automatically attaching the edges of the cloth to the endless members as the cloth enters the machine, means for automatically detaching the cloth from the endless members as the cloth leaves the machine at the wide end thereof, means for actuating the endless members including a single shaft and means for transmitting the rotary movement of said shaft to the endless members, spaced rollers at the front ends of the frames over which the cloth passes before passing between the frames, a vertically movable member located above the rollers, spaced rollers carried by said member, for pressing portions of the cloth between the first mentioned rollers when said member is lowered, means for raising and lowering said member, transversely arranged supporting members on which the frames are slidably arranged, manually operated means for moving the frames toward and away from each other on said supporting members, means for driving the said single shaft including speed regulating means, a floating roller over which the cloth passes as it leaves the frames and means operated by the movement of said roller for actuating the speed regulating means.
